ATTORNEY

UNITED STATES PATENT OFFICE

HERMAN JOHN HAMMERLY, OF WALLINGFORD, CONNECTICUT, ASSIGNEE TO THE TRUMBULL ELECTRIC MANUFACTURING COMPANY, OF PLAINVILLE, CONNECTICUT, A CORPORATION OF CONNECTICUT

KNIFE SWITCH

Application filed May 3, 1929. Serial No. 360,124.

This invention applies to electric switches of the knife blade type having pivotally mounted blades which are usually enclosed and which are actuated by an external handle having an internal crank portion to which portion the blades are connected.

In such construction it is desirable that the blades be connected to the crank portion of the operating member by means of individual insulating connectors so that the blades have no direct connection with each other at their free ends.

Ordinarily it is desirable to use the individual type of insulating connectors but in some instances it has been found desirable to also connect or tie the free ends of the blades to each other in order to secure and to maintain alignment and accuracy in their relative lateral spacing.

For the reason that the blades of enclosed knife switches are necessarily made as short as possible, it would be impractical to attach a connecting cross bar of any prior known form to the ends of the sides of the blades in addition to the individual insulating crank connectors and such construction would not only be prohibitively expensive but it would also be a cumbersome and ungainly construction which would conceal the switch contacts to a considerable extent and thus prevent the necessary visibility of the blades and contacts while the switch is being operated for inspection.

One of the objects of my invention is to provide a knife switch construction in which each blade is provided with an individual crank connector and also a tie bar for connecting and positively spacing the free ends of the several blades laterally with respect to each other.

Another object is to provide a tie bar means for positively spacing the free ends of the switch blades with respect to each other and which means, in its preferred forms, may be readily attached or detached either before or after the blades and contacts have been mounted on the switch base.

Another object is to provide a readily detachable tie bar means which may be secured

in position entirely without the use of screws, nuts or rivets.

Another object is to provide a tie bar of such comparatively small dimensions that it will not obstruct the view of the switch blades or other parts to any objectionable extent.

Another object is to provide a tie bar which may be secured to the respective blades without cutting away any of the current carrying portion of the blades and without requiring the use of a special die stamped blade.

In the preceding paragraphs I have referred to my blade connecting member as a "tie bar" in order to clearly distinguish it from the generally known forms of cross bars.

In prior switch constructions in which cross bars are used, the construction is almost invariably such that the cross bar must receive the operating impact and strains of the switch but in my present construction, the tie bar merely functions to positively position the switch blades laterally and it is entirely relieved from any operating stress or strains whatever and, further, by reason of not being subject to the usual operating strain, the bar may be much smaller in cross sectional dimensions and therefore much less expensive.

The general construction of a switch and enclosing box in which my invention may be used may be, for instance, similar to that disclosed in my co-pending application Ser. No. 335,250, filed January 26, 1929, and may or may not include a quick-break mechanism and the members for connecting the blades and the operating crank may be, for instance, similar to those disclosed in my co-pending application Ser. No. 335,891 filed Jan. 29, 1929.

According to my improvement the various switch blades are independently connected with an operating crank by means of insulating plates or connectors and these plates and the blades are connected together by means of a tie rod which is separate and independent of the crank. This tie rod may be connected to the plates and blades in various

ways as shown in the accompanying drawings.

Fig. 1 is a perspective view of an enclosed switch embodying one form of my invention, 5 the switch being shown closed but the box being shown open. This switch includes three knife blade units.

Fig. 2 is a transverse section showing the tie bar construction.

10 Fig. 3 is a side view and section showing a single knife switch unit in closed circuit position.

Fig. 4 is similar to Fig. 3 but with the blade raised or in open circuit position.

15 Figs. 5, 6, and 7 are detail sectional views of these different forms of connection between the tie bar and the blade and connector.

Fig. 8 shows a pair of blades connected by 20 another form of tie bar.

Fig. 9 is a perspective view of parts of the tie bar of Fig. 8.

The invention is shown and described with reference to an enclosed switch having a box 25 10 of any suitable type. The parts of the switch proper are mounted on an insulating base 11 and may include any number of switch units each of which has a lower terminal 12, an upper terminal 13 and will usually have fuse clips such as 14 and 15 for any suitable type of fuse. Each switch unit includes a stationary hinge post 16 and the usual spring contact jaws 17 together with a blade 18 which is hinged in this case to the 30 lower stationary post 16.

An insulating plate 19 preferably formed of fibre or similar material is riveted or otherwise secured to each blade and adapted for connection to an operating crank 20. This 40 crank may be pivotally supported in the walls of the box or otherwise in any suitable manner. In the form shown each plate is provided with a notch 21 to receive the cross bar of the operating crank.

15 The switch is adapted to be operated by an external handle 22 and may have any suitable form of quick make and break mechanism 23 interposed between the handle and the operating crank.

20 Each of the plates 19 is preferably extended beyond the blade and has a foot portion 24 serving as an abutment member to engage the base in the circuit closing movement. This 55 non-metallic plate thus serves as a shock absorber to take up the impact of the switch mechanism and prevents breaking or chipping the base and injury to the metallic parts.

The various connector plates 19 are tied 60 together laterally by means of a bar 25 also preferably formed of insulating material. This bar may be connected to the blades and plates in various ways. In the preferred form each plate 19 is provided with a transverse opening 26 which is large enough to receive 65 the tie bar 25 and the tie bar is provided

with a notch 27 preferably positioned for each of the switch blades. In the form shown in Figs. 1 to 4 inclusive, the tie bar is held in position by means of a series of spring clips 28. Each clip interlocks with one edge of the opening 26 and has arms which press against the tie bar to hold the tie bar interlocked with one edge of the switch blade as shown in Fig. 2. It will thus be seen that the switch blades are held at their proper distances apart so that even if one switch blade should become loose with respect to its hinge pin or pivot it will nevertheless be maintained in its proper relative position for engagement with its cooperating switch jaw.

The tie bar being readily insertable and removable, it is possible to disconnect the bar and replace or repair one of the switch blades if necessary, and then replace the bar.

25 In the form of connection shown in Fig. 5 the hole 26 in the connector plate 19 is filled by supplemental filler strip 30 which is passed through after the tie bar is inserted and may conveniently be secured in place, for instance, 90 by means of a cotter pin 31.

30 In the form shown in Fig. 6 a clip 33 is inserted in the opening 26 after the tie bar is placed in position and is then clamped or riveted over on to the opposite sides of the plate 19 to hold itself and the tie bar in fixed position.

35 In the form shown in Fig. 7 the tie bar is inserted into the opening 26 in the connector plate and the switch blade 18 is then inserted in the notch 27 in the tie bar and the connector 19 is then secured to the blade, for instance, by means of one or more rivets 35.

40 In the form shown in Fig. 8 the tie bar is made up of sections 37. These may be secured to one plate 19 by means of an anchor piece 38 which extends through the connector 19 and through the blade 18 and is held in place by a rivet 39. Two adjacent sections of the tie bar may be secured together by an anchor 45 age or tie plate 40 which extends through one of the connectors 19 and the corresponding switch plate 18 and is held by rivets such as 41.

45 Among the advantages of my invention 115 are that, while it functions perfectly to accurately space the respective switch blades, it is very much cheaper than a cross-bar of the former types—it may or may not be included in a switch construction as desired. 120 In its preferred forms it may be readily attached or detached either before or after the blades are mounted on the base and without the use of tools or machinery and it entirely eliminates the use of screws, nuts or rivets—125 it is entirely relieved from an operating stress or strains and it may be included in the switch construction without cutting away any of the current carrying portion of the blades. 130 Such a tie bar construction can be readily ap-

plied to existing constructions. It is also adapted to convenient repair and replacement.

It should be understood that various other methods of connection between the connector plates 19 and the switch plates 18 may be provided within the spirit and scope of my invention.

I claim:

10 1. In a knife switch an insulating base, a plurality of switch blades mounted thereon, an insulating connector plate secured to each blade, an operating crank connected with all of said connector plates and a separate tie 15 bar interlocking with and laterally spacing all of said blades independently of said crank.

2. In a knife switch, an insulating base, a number of hinged blades mounted on said 20 base, an insulating connector plate secured to each blade, an operating crank independently coacting with said connector plates and a readily removable tie bar for connecting and laterally spacing all of said blades.

25 3. In a knife switch an insulating base, a plurality of hinged blades mounted on said base, an insulating connector plate secured to each blade, an operating crank connected with all of said connector plates and a separate readily removable tie bar connecting and laterally spacing all of said blades and connector plates.

35 4. A knife switch construction including an insulating base, a plurality of hinged blades separately mounted on said base, an insulating connector plate secured to each of said blades and having an extended portion to abut against said base to form a stop for said blades when in the ON position, an operating crank having connection with all 40 of said connector plates and a separate tie bar interlocking with each of said blades and laterally spacing the respective blades and connector plates.

45 5. In a knife switch, an insulating base, a number of blades mounted on said base, an insulating connector plate secured to each blade, an operating crank coacting with all of said connector plates and a separate tie bar 50 detachably connecting and positively spacing all of said blades and the respective plates.

60 6. In a knife switch, an insulating base, a number of blades mounted on said base, a connector plate secured to each blade, an operating crank having operable connection with all of said connector plates, a tie rod passing through said plates and interlocking with said blades for connecting and laterally spacing said blades and means for clamping said rod in position.

65 7. In a knife switch, an insulating base, a number of blades mounted on said base, a connector plate secured to each blade, an operating crank coacting with all of said con-

necting plates, a tie rod passing through said plates for connecting the same and a spring member for detachably clamping said rod to said plates.

70 8. In a knife switch, a plurality of switch blades, an insulating connector plate secured to each blade, an operating crank coacting with all of said connector plates, a tie rod passing through said plates for connecting the same and a detachable spring secured to each of said plates and adapted to engage said rod to yieldingly hold the rod in position.

75 9. In a switch, a plurality of switch units, each consisting of a hinged blade and an insulating connector rigidly secured thereto, a notched tie bar connecting all of the switch units and spacing them at fixed distances from each other and an operating crank coacting with said connectors.
